Primary Examiner — Dana L Meyrow(74) *Attorney, Agent, or Firm* — Shook, Hardy & Bacon L.L.P.(57) **CLAIM**

The ornamental design for a container for foodstuff, as shown and described.

DESCRIPTION

FIG. 1 is a front side elevation view of a container for foodstuff of the present invention, the rear, right side and left side elevations being identical thereto;

FIG. 2 is a bottom perspective view thereof; and,

FIG. 3 is a bottom plan view thereof.

The top plan view has been omitted as it forms no part of the design.

The evenly-dashed broken lines in the drawings illustrate the portions of the container for food stuff that form no part of the claim. The dot-dot-dash broken lines in the drawings define the bounds of the claim and form no part thereof.

The surface shading lines on the claimed portion are provided only to indicate the character and/or any contour or curvature of the surfaces. They do not indicate color, texture, markings that actually exist thereon, indicia, graphic representations, surface treatment, or any other ornamentation applied to the article.
